DESIGN.

M. GIBNEY.

SILVER FORK AND SPOON.

No. 59.

Patented July 10, 1846.

A new form and embellishment for Silver
Forks Spoons Ladles &c by Michael Gibney No. 59

Des. 59

Michael Gibney, New York City.

Letters Patent (Design No. 59) dated 10th July 1846

The schedule referred to in these Letters Patent and making part of the same.

To all whom it may concern:

Be it known that I, Michael Gibney, of the City & State of New York, have invented a new and improved shape and embellishments for the handles of Silver forks, Spoons, Tlasses and other articles of table use, to which they will apply, and I do hereby declare the following is a full and exact description of the same, reference being had to the annexed drawings which make a part of this Specification.—

The shank of the handle is slightly curved on its edges and does not differ in that respect from the ordinary ones. My invention is therefore confined to the form of the head of the handle and the embellishments embossed on the back and front of it and the shank.— The head of the handle gradually expands into an elliptical form and the embellishments which are in the Louis 14th. style of art, are embossed upon the back and front of the handle.— The embellishments on the back and front of the head of the handle are composed of thin scrolls curving inwards, the scrolls on the front having at their junctions top & bottom an ornamental honeyuckle

Dec. 59

The back and front of the shank have each a leaf extending the whole length of the former terminating with ornamental curves.

Fig. 1 is the front view of a Fork, and the section a, a, colored red, shows the concavity of the leaf and the form of the edges of it. A, A, is the shank, B, B, is the head of the handle.

Fig. 2, is a back view of the same fork, the section b, b, colored red, showing the concavity of the leaf and the form of its edges.

Fig. 3 shows the form of the fork in the direction of its length. —

Claim —

What I claim and desire to secure by letters Patent is the form of the head as herein set forth to be applied to the handles of Silver forks, spoons, Ladles and other articles of table use, together with the application of the embellishments herein described to be embossed on the handles, back & front, of the within named articles for table use.

Ex'd Witnesses,
John Edw^r. Jones
